COMBINED COASTER SET AND HOLDER

Gustav Robert Svensson, Yokohama, Japan, assignor to
Julie Pomerantz, Inc., New York, N.Y.

Filed Mar. 12, 1973, Ser. No. 340,260

Term of patent 14 years

Int. Cl. D7—99

U.S. Cl. D7—45

FIG. 1 is a perspective view of a combined coaster set and holder, showing my new design, one of the coasters having been removed from the holder for sake of illustration; it being understood that the coasters are identical in appearance and the rear and bottom surfaces thereof are substantially plain and unornamented;

FIG. 2 is a rear elevational view thereof;

FIG. 3 is a top plan view thereof;

FIG. 4 is a front perspective view of a modified form of the design of FIG. 1 showing a longer holder with two columns of coasters therein; the side and rear are substantially similar to that of the design shown in FIGS. 1 and 2.

I claim:

The ornamental design for a combined coaster set and holder, substantially as shown and described.
